United States Patent Office

Des. 211,789
Patented July 30, 1968

211,789

BATHTUB

Horst Godfrey Bonsack, 51 South St., Flat 17,
London, England

Filed Feb. 1, 1967, Ser. No. 5,656

Claims priority, application Great Britain Sept. 12, 1966

Term of patent 14 years

(Cl. D23—55)

FIG. 1.

FIG. 2.

FIG. 3.

FIG. 4.

FIG. 5.

FIG. 6.

FIG. 7.

FIG. 8.

FIG. 9.

FIG. 1 is a front elevational view of a bathtub showing my new design;

FIG. 2 is a rear elevational view thereof;

FIG. 3 is a top plan view thereof;

FIG. 4 is a bottom plan view thereof;

FIG. 5 is an elevational view taken from one end thereof;

FIG. 6 is an elevational view taken from the end opposite that shown in FIG. 5;

FIG. 7 is a cross sectional view taken on line 7-7 of FIG. 3;

FIG. 8 is a cross sectional view taken on line 8-8 of FIG. 3;

FIG. 9 is a cross sectional view taken on line 9-9 of FIG. 3;

FIGURE 10 is a top plan view of a modified form of the bathtub as shown in FIGURES 1-9; and

FIGURE 11 is a bottom plan view of FIGURE 10.

The characteristic feature of my invention resides in the arm rest in association with the bathtub as shown.

I claim:

The ornamental design for a bathtub, as shown and described.
